UNITED STATES PATENT OFFICE.

HOLLY M. VERPLANCK, OF LANSING, MICHIGAN, ASSIGNOR TO LANSING COMPANY,
OF LANSING, MICHIGAN.

TRUCK.

1,150,082.

Specification of Letters Patent. Patented Aug. 17, 1915.

Application filed September 21, 1912. Serial No. 721,534.

To all whom it may concern:

Be it known that I, HOLLY M. VERPLANCK, a citizen of the United States, residing at the city of Lansing, county of Ingham, and State of Michigan, have invented certain new and useful Improvements in Trucks, of which the following is a specification.

This invention relates to improvements in trucks.

10 The main object of this invention is to provide an improved all metal truck which is simple in structure and comparatively light in weight, and at the same time, one which is capable of carrying heavy loads 15 and notwithstanding very severe strains.

Further objects, and objects relating to structural details, will definitely appear from the detailed description to follow.

I accomplish the objects of my invention 20 by the devices and means described in the following specification.

The invention is clearly defined and pointed out in the claim.

25 A structure which is a preferred embodiment of my invention is clearly illustrated in the accompanying drawing forming a part of this specification, in which:

Figure I is a side elevation of a structure embodying the features of my invention, a 30 part of the handle being broken away. Fig. II is an inverted view of the structure shown in Fig. I. Fig. III is a vertical longitudinal section on a line corresponding to line 3—3 of Fig. II. Fig. IV is an enlarged detail 35 horizontal section on a line corresponding to line 4—4 of Fig. I, showing the manner of joining the frame, end and side pieces. Fig. V is an enlarged detail vertical section on a line corresponding to line 5—5 of Fig. 40 I. Fig. VI is a detail vertical section on a line corresponding to line 6—6 of Fig. I. Fig. VII is a detail vertical section on a line corresponding to line 7—7 of Fig. VI, showing details of the caster. Fig. VIII is a perspective view of one of the bolster brackets. Fig. IX is a perspective view of the bolster bracket shown in Fig. VIII reversed.

In the drawing similar reference characters refer to similar parts throughout the 50 several views, and the sectional views are taken looking in the direction of the little arrows at the ends of the section lines.

Referring to the drawing, the body of my improved truck consists of a frame compris-

ing side pieces or members 1 and end pieces 55 or members 2. These frame pieces are formed of channel iron, the side pieces being arranged with the channels facing outwardly and with the end pieces with the channels facing forwardly. The side and 60 end pieces are connected by the angled corner irons 3, the parts being connected by bolts or rivets, as clearly shown in Fig. IV.

The platform 4 is of sheet steel and is securely riveted to the top arms of the side and 65 end pieces of the frame so that it constitutes a bracing member therefor. The end pieces are arranged so that the ends of the side pieces project beyond the same as clearly shown in Figs. II and III.

The wheels 5 are mounted on the axle 6 which is rigidly supported by the hangers 7 mounted on the cross pieces 8. These cross pieces 8 are formed of angle irons arranged with their angles facing, the angle irons being secured on the under sides of the side pieces.

The hangers 7 are secured in the angles of the cross pieces 8 and in a spaced relation to the side pieces of the frame, the spindles of 80 the axles being on the outer sides of the hangers, so that the wheels can be arranged on the outer sides of the hangers as illustrated. The cross pieces, hangers and axle constitute a frame member.

The bolster piece 9 is secured to the bottom arms of the side pieces by the bolts 10 which extend therethrough and through the 90 filler blocks 11 arranged in the channel of the bolster at its ends. The bolster is supported by brackets on each side, each bracket comprising a horizontal arm 12 and a vertical arm 13 disposed at right angles to each other and connected by the webs 14.

The arms 12 of the supporting brackets 95 are arranged against and secured to the under sides of the side pieces while the arms 13 are arranged against the sides of the bolster, each pair of brackets being secured by bolts 15 arranged through the bolster. See Fig. II.

The horizontal arms of the brackets are provided with upwardly projecting ears 16 which are secured to the inner sides of the side pieces by the bolts 17. The bolster is 105 thus very rigidly supported and constitute frame member.

The caster wheels 18 are secured to the

bolster by the bolts 19. As the details of the casters form no part of my present invention, I do not describe the same herein.

The standards 20 of the handle are secured to the forwardly projecting ends of the side pieces by the bolts 21 and are provided with rearwardly turned arms 22 on their lower ends which are secured to the webs 14 of the front bolster supporting brackets by the bolts 23. The standards are connected by the cross piece 24 and the diagonally disposed braces 25.

The rear end piece is provided with stake sockets 26 and with a centrally disposed 15 draft bolt 27 having an eye in its outer end.

By thus arranging the parts, I provide a truck which is simple in structure and one which is capable of carrying very heavy loads and withstanding severe strains.

Having thus described my invention, what I claim is new and desire to secure by Letters Patent is:

In a truck, the combination with the body

frame comprising side pieces; of a bolster secured to said side pieces; angled bolster 25 brackets having webs connecting their arms, disposed on both sides of said bolster with their horizontal arms secured to the bottom of the side pieces and with their vertical arms secured to the said bolster, the horizontal arms of said brackets being provided with ears secured to the inner sides of said side pieces, whereby said bolster piece is braced and supported and constitutes a frame member; and a handle comprising a 35 pair of standards secured to the front ends of the side pieces and the webs of the bolster brackets and aiding in bracing said bolster.

In witness whereof, I have hereunto set my hand and seal in the presence of two witnesses.

HOLLY M. VERPLANCK. [L. s.]
